MANUALLY-OPERATED BOTTLE LOADER

John Larmett and John S. Larmett,
Waterbury, Conn.

Application June 19, 1945, Serial No. 600,352

6 Claims. (Cl. 294—87)

1

This invention relates to bottle handling apparatus, and more particularly to a manually-operated bottle loader for transferring simultaneously a plurality of bottles in two rows from a container to an endless conveyor for feeding the bottles into a washing, filling, and capping machine.

One object of the present invention is to provide a bottle loader of the above nature which is provided with two parallel rows of holes for receiving six bottles each, said bottles being held upon the loader by means of a pair of spring-pressed wings which are normally inclined upwardly and out of engagement with the bottle tops, but which may be pressed downwardly into horizontal position by the operation of a handle, into engagement with the necks of said bottles.

A further object is to provide a device of the above nature which will be simple in construction, inexpensive to manufacture, easy to install and manipulate, compact, ornamental in appearance, and very efficient and durable in use.

With these and other objects in view, there has been illustrated on the accompanying drawing one form in which the invention may conveniently be embodied in practice.

In the drawing,

Fig. 1 represents a perspective view of the improved manually-operated bottle loader as it appears when empty.

Fig. 2 is a fragmentary sectional view of the same, taken along the line 2—2 of Fig. 1.

Fig. 3 is a transverse sectional view of the same, taken along the line 3—3 of Fig. 1, as it appears when the bottle loader has been lowered in position upon the necks of the bottles, but before the wings have been swung downwardly into horizontal locking position.

Fig. 4 is a similar transverse sectional view of the bottle loader, as it appears when the upper handle section has been pressed to swing the wings downwardly into engagement with the necks of the bottles under the tops beads thereof.

Referring now to the drawing in which like reference numerals denote corresponding parts throughout the several views, the numeral 26 indicates the base of the bottle loader having a fixed bottom guide bracket 11 of closed rectangular formation secured thereto as by three lock screws 32 located in tapped holes 33, in said base 26.

Provision is also made of a depressible yoke member 14, having a top horizontal handle bar 10 and a pair of L-shaped depending side sections provided with outstanding bars 14a, 14b for em-

2

bracing the vertical sections of the fixed bottom member 11.

Provision is also made of a pair of transverse cross bars 12, 13 secured underneath the outstanding bars 14a, 14b, as by screws 14c, which cross bars are adapted to rest upon two pairs of normally upwardly inclined wings 15, 16 and 17, 18, said wings having notches 19, 20, and 21, 22 arranged in alignment with a plurality of apertures 27 formed in the base 26.

The bottle loader is adapted to be lowered upon a plurality of empty bottles B arranged in a flat container, usually holding two dozen bottles in two rows of twelve each, said bottles having top beads 25 below which are shoulders 24 and reduced necks 23. The horizontal hand-engaging sections of the movable yoke member 14 and the guide bracket 11 are normally pressed apart into the position shown in Figs. 1, 2, and 3, by means of a pair of vertical coiled springs 26a located adjacent the ends of said sections. The vertical sections of the yoke member 14 are embraced by two pairs of side ears 14d integral with the guide bracket.

In order to maintain the wings 15, 16, 17, 18, normally in the inclined positions shown in Figs. 1—3, provision is made of four elongated hinge pins 28 which extend the full length of the base 26 and serve to connect the side wings 15, 18 to a pair of vertical hinge plates 29, secured to the base 26 by screws 30. The other two wings 16, 17 are secured to the base 26 by a pair of central overlapping horizontal hinge plates 29a held in place by the lock screws 32, which also attach the guide bracket 11 to said base.

Provision is also made of a plurality of springs indicated by the numerals 31, said springs having engagement with the undersurfaces of the wings 15, 16, 17, 18, as clearly shown in the drawing. The springs 31 also have engagement with the horizontal upper surface of the base 26 (as shown in Figs. 3 and 4).

The springs 31 serve to urge the bottle-engaging wings 15, 16, 17, 18 to open positions at all times, and are sufficiently strong so that when the handle 10 is released by the operator, the weight of the bottles will be overcome and they will drop out of the loader upon the conveyor belt or other support. In other words, in order to hold the bottles in the loader, it is necessary for the operator to keep the handle 10 depressed at all times.

In order to limit the yoke 14 in its reciprocating up and down movements, provision is made of a plurality of guide bolts 34 having heads 35 and

threaded lower sections 36 which are adapted to be secured in tapped holes 37 in the base 26.

Operation

In operation, when it is desired to manually transfer two rows of six bottles simultaneously from the bottle container to the conveyor belt which carries the bottles to the bottling apparatus, the operator will grasp the double handles of the loader and lower it to the position shown in Fig. 3. He will then press the top section 10 of the yoke 14 downwardly toward the horizontal top section of the fixed lower bracket 11. This will cause the two cross bars 12, 13 carried by the outstanding bars 14a, 14b of the yoke 14 to engage the inclined wings 15, 16 and 17, 18 and swing them downwardly to the horizontal position shown in Fig. 4. The notches 19, 20, 21, 22 will then engage the necks 23 of the bottles B below the shoulders 24 of the enlarged top beads 25 of the bottles B.

The operator will then carry the entire loader, including the base 26 and the two rows of six bottles from the case of empties to the end of the conveyor belt. The yoke 14 will then be released, whereupon the wings 15, 16, 17, 18 will be pressed upwardly by spring action, to the unlocked inclined positions shown in Figs. 1, 2, and 3, permitting the bottles to be deposited on the conveyor.

One advantage of the present invention is that it entirely eliminates physical contact of the operator's hands with the bottles which are frequently chipped and have sharp edges which would cut the operator's fingers.

A further advantage is that the use of the improved loader speeds up the work of the bottling plant tremendously, permitting one operator to do the work of three, as in the previous practice.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a bottle loader for simultaneously transferring a plurality of bottles having enlarged upper beads from one place to another, a base having a row of spaced apertures shaped to embrace the enlarged upper beads of said plurality of bottles when lowered thereupon, a pair of initially upwardly-inclined wings hinged to said base and located upon opposite sides of said apertures, relatively strong spring means to press said wings upwardly to non-bottle-holding position, and manually operated compressible means for swinging said wings downwardly to cause them

to engage under the enlarged upper beads of said bottles, temporarily, to permit said bottles to be lifted when said loader is raised, said bottles being released automatically by the action of said spring means which is sufficiently strong to overcome the weight of said bottles.

2. In a bottle carrier for simultaneously transporting a plurality of bottles having enlarged upper beads from one place to another, a base block having a pair of parallel rows of spaced apertures shaped to loosely embrace the beads of a plurality of bottles arranged in alignment with said apertures, two pairs of initially upwardly-inclined wings hinged to said base block and located upon opposite sides of said rows of apertures, relatively strong spring means to normally press said wings upwardly to non-bottle-holding position, and a manually-operated compressible cross bar for swinging said wings downwardly to cause them to engage temporarily under the enlarged upper beads of said bottle tops and permit said bottles to be lifted when said loader is raised, said spring means having sufficient strength to overcome the force due to the weight of said bottles when said handle is released.

3. The invention defined in claim 1, in which said means comprises a pair of cross bars for engaging said wings and handle means to force said cross bars downwardly.

4. The invention defined in claim 1, in which said spring means comprise spring hinges for securing said wings to said base, and in which a pair of manually-operated compressible cross bars are provided for forcing said wings downwardly against the action of said spring hinges.

5. The invention defined in claim 1, in which said spring means comprise spring hinges for securing said wings to said base, and in which a pair of manually-operated compressible cross bars are provided for forcing said wings downwardly, against the action of said spring hinges, and spring means for pressing said cross bars upwardly.

6. The invention as defined in claim 1, in which notches are provided in said wings in alignment with the apertures in said base.
